PLASTIC CONTAINER FOR LIQUIDS

William J. Holcroft and Richard C. Rheinhart, North Aurora, and Jerald E. Briggs, West Chicago, Ill., assignors to American Can Company, New York, N.Y.

Filed Jan. 9, 1970, Ser. No. 20,849

Term of patent 14 years

Int. Cl. D7—99

U.S. Cl. D49—29

FIG. 1

FIG. 2

FIG. 3

FIG. 4

FIG. 5

FIG. 1 is a top plan view of a plastic container for liquids showing our new design;

FIG. 2 is a bottom plan view thereof;

FIG. 3 is a side elevation view thereof;

FIG. 4 is another side elevation view showing the plastic container for liquids rotated 90° from its position shown in FIG. 3; and

FIG. 5 is a fragmentary sectional view taken along the line 5—5 of FIG. 3.

We claim:

The ornamental design for a plastic container for liquids, substantially as shown.
